UNITED STATES PATENT OFFICE.

ROBERT LAW, OF WOODSIDE, AND EDWARD JOHN SWEDA, OF GLENDALE, NEW YORK.

MULTIPLE SWITCH.

Application filed September 11, 1926. Serial No. 134,910.

This invention relates to electrical switches, and has especial reference to multiple switches of the push and turnbutton type.

One of the principal objects of the present invention is the production of a multiple switch especially adapted to be included in a vehicle direction signaling apparatus for controlling a plurality of signals, such as electric lamps, and with which a person may 10 "feel" the way to the signal actuating positions of the button or manipulator of the switch, and therefore be at all times assured that the intended signal is being operated.

With the foregoing and other objects in view, the invention resides in the particular provision, construction and functions of the parts hereinafter fully described and illustrated in the accompanying drawings, in which—

20 Figure 1 is a central vertical sectional view through the switch of the present invention, and showing the movable contact thereof in one of its circuit closing positions.

Fig. 2 is a transverse sectional view taken 25 on the line 2—2 of Fig. 1.

Fig. 3 is a transverse sectional view taken on the line 3—3 of Fig. 1.

Fig. 4 is an elevation of the under side of the ground plate and certain parts associated 30 therewith.

Fig. 5 is a side elevation of the ground plate.

Fig. 6 is an elevation of an assemblage of parts carried by the insulator base of the 35 switch.

Fig. 7 is a perspective view of the movable contact.

Fig. 8 is a perspective view of the yieldable stops and carrier therefor.

40 Figs. 9, 10, and 11 are different elevations of the hollow slidable shaft or arbor of the switch.

Fig. 12 is an inverted plan view of the arbor spring tensioning member.

45 Figs. 13 and 14 are views respectively of the two slide operating cams.

Fig. 15 is a view illustrating the slide operating cams in place on the end of the arbor which permits movement thereof.

50 Figs. 16 and 17 are views respectively of the cam actuated slides.

Fig. 18 is an inverted plan view of the insulator base.

The switch of the present invention, as 55 stated, is of the push and turnbutton type, and is adapted to make and break a plural-

ity of circuits by pushing inwardly on the button of the switch and by turning the button to "on" or circuit closing positions, and to "off" or circuit opening position. The 60 turning movement of the button, in the present instance, is within the limits of a radius of substantially 180°, and it will therefore be necessary, in accordance with one feature of the invention to turn the button clockwise or to the left to one of the circuit closing positions, and counter-clockwise or to the right to another circuit closing position, so that a person will at all times be able to close a circuit through a particu- 70 lar signal without being aided by any visual indications on parts of the switch, but will be able to "feel" the way in the selection of the particular circuit to be closed. The button of the switch may be turned left and 75 right to alternately close a plurality of circuits, said button having an intermediate position in which the circuits will be open.

In the illustrated embodiment, the switch includes a shell 10 of sectional construction 80 and comprises an attaching part 11, an annular part 12 of insulating material, and a removable cap 13. Arranged in the bottom of the shell and resting on the part 11 is a base 14 of insulating material. The base 14 85 has secured thereto contacts 15 whose terminals 16 are disposed above the top face of the base 14 and are arranged diametrically opposite each other. Each of the contacts 15 is a fixed contact and will be electrically connected in a circuit with a suitable signal to be actuated when engaged by the movable contact 17 of the switch. The movable contact 17 is shown most clearly in Fig. 7 and will be constructed to 95 provide relatively flexible fingers 18, depending spaced parallel flanges 19, an upper standing lug 20 and a circular opening 21. A push and turnbutton 22 is provided and is guided for movement by the wall of a 100 circular opening in the cap 13. Arranged axially of the button 22 and secured thereto so as to move therewith is a shaft 23. Arranged for sliding movement on the shaft 23 is a hollow shaft or arbor 24. The arbor 24 105 is prevented from having turning movement with respect to the shaft 23 by virtue of a pin 25 which extends transversely through the shaft 23 and has the opposite ends thereof respectively disposed in slots 26 in the upper end of the arbor 24. The movable contact 17 is arranged on the arbor 24 by

- virtue of the opening 21 therein and is capable of turning with respect thereto. A tensioning element 27 is arranged on the arbor 24 and is held against turning movement with respect thereto by virtue of the "flats" 28 and 29 respectively on the arbor 24 and the element 27. The element 27 and the movable contact 17 are correlated, and both will be under the influence of a coil 10 spring 30 which surrounds a spacer 31 on the arbor 24. The spacer 31 is arranged between portions of the movable contact 17 and the tensioning element 27 so as to hold them in spaced relationship. One terminal 15 32 of the spring 30 is in engagement with a lug 33 on the element 27, and the other terminal 34 of the spring 30 is in engagement with the lug 20 of the movable contact.
- 20 In order to releasably maintain the movable contact in the circuit closing positions with respect to the terminals 16, and in the intermediate circuit opening position, there is provided a means presently to be described. On the lower end 35 of the arbor 24, which end is of arcuate formation, are cams 36. The cams are similar in construction, each being provided with an opening which conforms to the arcuate end 35, and 25 to the lower end of the shaft 23. The cams 36 will be oppositely disposed on the end 35. The cams 36 coact respectively with portions of slides 37 and 38. The slide 37 is provided with a depending lug 39 and a central opening 40 in which its cam 36 is disposed so as to coact with the walls thereof. The slide 38 is substantially similar in construction to the slide 37 and has a depending lug 41, and an opening 42 which receives its cam 36 so as to coact with the walls of the opening. The slide 38 differs from the slide 37 in that the former has a notch 43 for a purpose to appear. The slides 37 and 38 are arranged in superposed relationship between 30 the flanges 19 of the movable contact, with the cams 36 disposed respectively in the openings 40 and 42 of the slides. A collar 44 is secured to the lower end of the shaft 23. Secured to the base 14 is a ground plate 45, the plate being secured by screws 46 and a screw 47 which serves as a binding post for the ground connection. The cams 36 are arranged between a portion of the movable contact 17 and the plate 45. The plate 45 has a central opening through which the lower end of the shaft 23 extends, radial notches 48, and projections 49. The collar 44 limits the upward movement of the shaft 23 by engaging the plate 45. Arranged in 40 a recess in the base 14 is a carrier 50, shown most clearly in Figs. 3 and 8. The carrier is provided with guides 51 radially disposed which accommodate stops 52 for sliding movement, there being provided a spring 53 which constantly acts on the stop 52 to hold the stops in radially outward active positions. Each of the stops 52 is permitted to move radially inward against the action of the spring 53. The stops 52 extend respectively into the notches 48 of the plate 45 and project upwardly flush with the upper face of the plate, thus preventing the carrier from turning. Each of the stops 52 is adapted to coact with the lugs 39 and 41. Two of the stops 52 are arranged with respect to the terminals 16, whereas, the third stop will be midway of the other stops so as to coact with the lugs 39 and 41 to hold the movable contact in intermediate or circuit opening position as distinguished from the 45 circuit closing positions in which the movable contact will be held when the lugs 39 and 41 coact with the stops 52 adjacent the terminals 16.
- 50 The button 22 and its shaft 23 may be moved inwardly so as to cause the lower end of the shaft 23 to contact with a terminal screw 54 electrically connected to a member 55 with which connection is made to a suitable signal such as a horn. A spring 56 is employed for yieldably maintaining the button 22 in a normal position against the action of the inward pressure. The spring 56 surrounds the upper end of the arbor 24 and has one end thereof secured to the button as at 57.
- 55 With the movable contact 17 in circuit closing position in which the fingers 18 thereof are in engagement with one of the terminals 16, at the right side of the switch as illustrated in Fig. 1, it will be impossible to turn the button 22 counter-clockwise due to the fact that the lug 39 will move into contact with one of the projections 49 of the plate 45, and in so doing impeding the action of the cams 36 on the slides 37 and 38. However, when the button 22 is turned clockwise as indicated by the arrow in Fig. 2, or in other words to the left, the cams 36 will act on the slides to move them to cause the disengagement of the lugs 39 and 41 from the particular stop 52. The lugs 39 and 41 are disengaged from the particular stop 52 in succession, first one and then the other. Meanwhile the spring 30 is being placed under tension as the arbor 24 is turned to turn the cams 36, and as the lugs 39 and 41 clear the particular stop 52 the movable contact 17 will be suddenly snapped in the same direction in which the arbor was turned to a circuit opening position. The lugs 39 and 41 will then engage the intermediate stop 52 which will yield due to the inclined faces 58 on the insides respectively of the lugs 39 and 41. By repeating the turning movement of the button 22 in the same direction, namely, to the left the movable contact will be snapped to a position in which the fingers 18 will engage the terminals 16 at the left of the switch. The button 22 will be prevented 60 from turning clockwise due to the action of the spring 56.
- 65

from having further turning movement to the left or clockwise by virtue of the engagement of the lug 41 with one of the projections 49 adjacent the last mentioned terminal 16. The button 22 will thus be prevented from turning completely around, but will be limited in its turning movement to substantially 180° within the limits of which two separate circuits may be closed by virtue 10 of the function of the movable contact 17, which can also be moved to a circuit opening position. Under this arrangement and functions of the parts a person may selectively close a plurality of circuits, and in 15 each case know exactly what particular signal is being rendered active by simply paying attention to the direction in which the button 22 is moved.

Having thus described our invention, we 20 claim:

1. In a multiple switch of the class described, a contact carrying arbor, means supporting the arbor for turning movement in opposite directions, cams movable with said 25 arbor, and said arbor being movable with respect to said cams, slides with portions of which said cams respectively co-act in the turning of said arbor, projections on said slides respectively, radially disposed stops, 30 means supporting the stops for movement in opposite directions, yieldable means acting on said stops to hold them in the active position, said projections being engageable with each of said stops to hold the slides 35 against turning movement, said projections being disengageable from each of said stops when engaged therewith in the sliding movement of said slides, and means acting on said slides causing said slides to turn rapidly 40 when said projections are disengaged from either of said stops.

2. In a multiple switch of the class described, a contact carrying arbor, means supporting the arbor for turning movement in 45 opposite directions, cams movable with said arbor and said arbor being movable with respect to said cams, slides with portions of which said cams respectively co-act in the turning of said arbor, projections on said 50 slides respectively, radially disposed stops, means supporting the stops for movement in opposite directions, yieldable means acting

on said stops to hold them in the active positions, said projections being engageable with each of said stops to hold the slides 55 against turning movement, said projections being disengageable from each of said stops when engaged therewith in the sliding movement of said slides, means acting on said slides causing said slides to turn rapidly 60 when said projections are disengaged from either of said stops, and means limiting the turning movement of said arbor in opposite directions.

3. In a multiple switch of the class described, a contact carrying arbor, means supporting the arbor for turning movement in opposite directions, cams movable with said arbor and said arbor being movable with respect to said cams, slides with portions of which said cams respectively co-act in the turning of said arbor, projections on said slides respectively, radially disposed stops, 70 means supporting the stops for movement in opposite directions, yieldable means acting on said stops to hold them in the active positions, said projections being engageable with each of said stops to hold the slides 75 against turning movement, said projections being disengageable from each of said stops when engaged therewith in the sliding movement of said slides, and means co-acting with portions of said slides to limit the turning movement of said arbor in opposite directions.

4. An electrical multiple switch including an arbor, fixed contacts arranged radially with respect to the axis of the arbor, a contact loosely arranged on said arbor for turning movement with respect thereto and adapted to be moved into and out of engagement with each of said fixed contacts, means between the arbor and the contact arranged thereon allowing movement of the arbor while said contact is held against movement, and releasable means for holding the last mentioned contact against turning while the arbor is turning, said first mentioned means being operative to turn said last mentioned contact when said last mentioned means has operated to release said last mentioned contact.
